UNITED STATES PATENT OFFICE.

RUFUS DEPEW, OF BROOKLYN, NEW YORK.

GAS-BURNER FOR HEATERS.

1,352,358.

Specification of Letters Patent.

Patented Sept. 7, 1920.

Application filed February 12, 1920. Serial No. 358,253.

To all whom it may concern:

Be it known that I, RUFUS DEPEW, a citizen of the United States, and a resident of the city of New York, borough of Brooklyn, in the county of Kings and State of New York, have invented a new and Improved Gas-Burner for Heaters, of which the following is a full, clear, and exact description.

10 The object of the invention is to provide a new and improved gas burner for use in the fire box of a kitchen range, house heating furnace and similar heater, and arranged to insure the production of a high 15 heat with an exceedingly economical consumption of gas.

Another object is to provide a gas burner which can be readily installed in a fire box without requiring alteration of the same.

20 Another object is to provide a gas burner which is not liable to burn out, hence insuring long life of the gas burner.

Another object is to provide a gas burner which is exceedingly simple in construction, 25 not liable to get out of order easily, and cheap to manufacture.

With these and other objects in view, the invention consists of certain novel features of construction as hereinafter shown and described and then specifically pointed out in 30 the claims.

A practical embodiment of the invention is represented in the accompanying drawings forming a part of this specification, in 35 which similar characters of reference indicate corresponding parts in all the views.

Figure 1 is an elevation of the rear end of the gas burner shown in position in the fire box of a kitchen range, the latter being 40 shown in section;

Fig. 2 is a plan view of the gas burner with the gas and air mixer and the range shown in section; and

Fig. 3 is an enlarged cross section of one 45 of the side tubes and one of the perforate pipes rising therefrom.

The gas burner in its general construction comprises two side tubes 10 and 11 and a top tube 12, the tubes being closed at one 50 end by suitable caps 13, 14 and 15 and being connected by elbow connections 16, 17 and 18 with a fixture 20 in the form of a T having an inlet 21 at the front end. The inlet 21 is connected by a nipple 25 into which fits 55 the reduced end 26 of a gas and air mixer 27 having a mixing chamber 28 connected by

openings 29 with the atmosphere. Into the mixing chamber 28 extends a nozzle 30 connected with a gas supply pipe 31 connected with a gas main or other suitable gas supply. 60 It will be noticed that by the arrangement described gas and air are mixed in the chamber 28 and this mixture passes by way of the nipple 25 into the fixture 20 from which the mixture is distributed into the side pipes 10 65 and 11 and the top tube 12.

From the side tubes 10 and 11 rise perforate pipes 40 and 41 closed at their upper ends and having their perforations 42 and 43 arranged in the direction of the length of 70 the side tubes 10 and 11, as will be readily understood by reference to Figs. 1 and 3. From the top tube 12 extend sidewise, upwardly and outwardly diverging perforate pipes 45, 46 closed at the upper ends and 75 having their perforations 47, 48 extending in an upward direction. The ends of the pipes 45 and 46 are in vertical planes adjacent the vertical planes in which the perforate pipes 40, 41 are located, and the said 80 upper ends of the pipes 45, 46 terminate a short distance above the upper ends of the upright pipes 40, 41. Perforate bottom pipes 50, 51 extend from the side tubes 10 and 11 toward each other, and the perforations 52 and 53 of the bottom pipes 50 and 51 are located on top. The ends of the pipes 85 50 and 51 terminate a short distance from the corresponding side tubes 10 and 11 and the said tubes 50 and 51 are arranged alternately one relative to the other, similar to the top pipes 45 and 46.

The side tubes 10 and 11 are spaced apart so as to extend close to the side walls 60 and 61 of the fire box 62 in which the burner 95 is installed, it being understood that the said tubes 10 and 11 and their bottom pipes 50 and 51 are arranged in the lower portion of the fire box while the upper ends of the pipes 40 and 41 terminate a short distance below the top 63 of the fire box.

It will be noticed that by the arrangement described the inflammable mixture of gas and air readily burns in small jets and with a blue flame at the perforations of the several pipes 40, 41, 45, 46, 50 and 51, and hence a large number of such burning jets are provided whereby an exceedingly high heat is distributed with an economical consumption of gas.

110 It is understood that the gas burner, with the exception of the nipple 25 and the mixer

27, extends within the fire box while the nipple extends through the door of the fire box to the outside thereof thus locating the mixer 27 likewise outside of the fire box for 5 convenient connection with a gas supply.

The gas burner shown and described is very simple in construction, being practically made of pipes and pipe fittings, and it can be cheaply manufactured and readily 10 installed in the fire box of a gas range, house heating furnace and other heater.

Having thus described my invention, I claim as new and desire to secure by Letters Patent:—

15 1. A gas burner for heaters, comprising side tubes and a top tube, the tubes being closed at one end and connected at the other end with a fixture common to the tubes, a gas and air mixer connected with the said fixture to supply the latter and the tubes with a mixture of gas and air, upright perforate pipes rising from the said side tubes, 20 perforate bottom pipes extending from the side tubes toward each other, and perforate pipes diverging sidewise upwardly and outwardly from the said top tube, the ends of the said diverging pipes extending in planes adjacent the planes of the said upright 25 pipes.

20 2. A gas burner for heaters, comprising side tubes and a top tube, the tubes being closed at one end and connected at the other

end with a fixture common to the tubes, a 30 gas and air mixer connected with the said fixture to supply the latter and the tubes with a mixture of gas and air, upright perforate pipes rising from the said side tubes, 35 perforate bottom pipes extending from the side tubes toward each other, and perforate pipes diverging sidewise upwardly and outwardly from the said top tube, the ends of the said diverging pipes extending in planes adjacent the planes of the said upright 40 pipes.

3. A gas burner for heaters, comprising side tubes and a top tube, the tubes being closed at one end and connected at the other end with a fixture common to the tubes, a 45 gas and air mixer connected with the said fixture to supply the latter and the tubes with a mixture of gas and air, upright perforate pipes rising from the said side tubes and having their perforations extending toward each other, perforate bottom pipes extending from the said side tubes toward each other but having their perforations at the top, and perforate diverging pipes extending upwardly and outwardly from the 50 said top tube and having their perforations extending upwardly.

RUFUS DEPEW.
